UNITED STATES PATENT OFFICE

115,878

DESIGN FOR A SLIPPER

Israel Berman, New York, N. Y.

Application June 14, 1939, Serial No. 85,481

Term of patent 3½ years

To all whom it may concern:

Be it known that I, Israel Berman, a citizen of the United States of America, residing in the city of New York, county of New York, and State of New York, have invented a new, original, and ornamental Design for a Slipper, of which the following is a specification, reference being had to the accompanying drawing, forming part thereof.

The figure is a perspective view of a slipper showing my new design.

I claim:

The ornamental design for a slipper, substantially as shown.

ISRAEL BERMAN.
